UNITED STATES PATENT OFFICE.

FRANKLIN HARDINGE, OF CHICAGO, ILLINOIS, ASSIGNOR TO HARDINGE BROTHERS, INCORPORATED, OF CHICAGO, ILLINOIS, A CORPORATION OF ILLINOIS.

OIL BURNER.

Application filed May 5, 1923. Serial No. 636,869.

My invention relates to improvements in oil burners, and is particularly concerned with the provision of novel means for controlling the flow of oil to the atomizing nozzle.

5 The objects of my invention are—

First; to provide an oil burner comprising an atomizing nozzle, a valve for controlling the flow of oil to the atomizing nozzle, and thermostatically controlled means for actuating said valve so as to vary the supply of oil fed to the atomizing nozzle in accordance with varying conditions of operation, and thus maintain a substantially constant 10 temperature.

Second; to provide an oil burner of the character described, by means of which the quantity of fuel supplied to the atomizer can be varied between two limits, one of which 20 may, if desired, be zero. I prefer, however, to so control the valve as to cause oil to be supplied to the atomizer at two different rates, one of which is greater than that required to maintain the desired temperature, 25 and the other of which is less than that required to maintain the desired temperature, the control apparatus being such that the rate at which oil is supplied to the atomizing nozzle is varied between these two limits so 30 as to maintain a substantially constant desired temperature.

Third; to provide means of the character described, for controlling the flow of oil to the atomizer, comprising means whereby the 35 rate of flow of oil to the atomizer can be varied so that the consumption at the two limiting positions of the control apparatus may be varied as desired.

Fourth; to provide means of the character 40 described for supplying fuel to an atomizer, comprising manually adjustable means which can be adjusted without disturbing the thermostatically controlled apparatus which normally adjusts the valve.

Fifth; to provide means of the character 45 described, which can be actuated by practically any of the known types of thermostatically controlled heat regulating apparatus, and

Sixth; to provide an apparatus such as 50 described, which is simple in construction, economical to manufacture and easy to operate.

Other objects of my invention will appear 55 as this description progresses. reference be-

ing had to the accompanying drawings, in which—

Figure 1 is a side elevation partially in section, showing certain details of construction of my improved apparatus;

60 Figure 2 is a plan view of a portion of the apparatus shown in Figure 1; this view also includes a diagrammatic illustration of the conventional thermostatically controlled heat regulating apparatus.

65 Figure 3 is a transverse section taken on line 3—3 of Figure 2, and

Figure 4 is a section taken on line 4—4 of 70 Figure 1, showing certain details of construction of the valve and the valve controlling apparatus forming a part of my invention.

Throughout the several views, similar 75 reference characters will be used for referring to similar parts as the several sections are taken looking in the direction of the small arrows.

In the drawings I have illustrated my invention as forming part of an oil burner, comprising a suitable base plate 5, on one 80 end of which is mounted the head 6 of the oil burner containing suitable gearing for transmitting the motion of the motor 7 through a shaft 8 contained in a housing 9 to the rotary atomizing nozzle 10. For supplying 85 oil to the atomizing nozzle, I provide a suitable storage tank 11, from which the oil is drawn by the rotary pump 12. In flowing to the pump 12, the oil passes through the intake pipe 13, a strainer 14, and a pipe 15. 90 The oil is discharged from the pump 12 through the pipe 16 into a pressure chamber comprising the two pipe sections 17 and 18, which are connected by the four-way union 19. The pressure tank thus formed is provided with an outlet pipe 20 shown in dotted outline, which extends down somewhat below the union 19, and the upper end of which is connected with the pipe 21 by the four-way 95 union 22. The pipe 21 leads to the control valve 23, the details of construction of which will be referred to later on.

The oil passes through the valve 23 and from this valve through the pipe 24 to a stand pipe 25, which extends up through the 100 head 6 and supplies oil to the rotary nozzle 10.

For maintaining the desired pressure upon the oil in the pressure chamber 18, I provide a pressure regulating valve 25' of any suit- 110

able construction, which connects one nipple of the four-way union 19 with the return pipe 26 which discharges in the storage tank 11.

5 The apparatus described above is purely conventional and well known to those skilled in this art, and further detailed description thereof appears to be unnecessary.

10 The valve which I employ for controlling the flow of oil to the atomizer comprises in general a chambered body member 27, having an inlet bore 28 and an outlet bore 29 in which is mounted a tubular valve seat 30, which is held in place by means of the 15 threaded plug 31. A valve stem 32 extends through the chamber in the member 28 and into the tubular valve seat 30. The other end of the valve projects outwardly through the opposite wall of the chambered body, and 20 is rotatably supported by means of the hollow plug 33, which is provided with a suitable stuffing box construction 34. The inner end of the valve stem 32 has a longitudinally extending bore 35 formed therein 25 and a transversely extending opening 36 which communicates with the longitudinally extending bore 35. A worm gear 37 is splined to the valve stem 32 adjacent its outer end and rests upon the outer end of 30 the stuffing box.

The chambered body 27 is provided with a laterally extending projection 38 which supports a bracket 39, in which is journaled a shaft 40, the inner end of which is provided with a worm 40' for rotating the worm gear 37. The outer end of the shaft has a grooved pulley 41 secured thereto, which is driven from the shaft 8 of the motor by means of another grooved pulley 42. By 40 the means just described, the valve stem 32 is continuously rotated while the burner is in operation, so as to prevent any sediment, dirt or other foreign matter from adhering to the valve stem and clogging the very 45 small opening 36. The details of construction of the valve just described are clearly set forth and claimed in my co-pending patent application, Number 544,002, filed March 15, 1922, and further description thereof appears to be unnecessary. The application just referred to also contains a disclosure of means for adjusting the valve stem in and out of the valve seat 30, so as to uncover more or less of the opening 36 and thereby 50 control the rate of flow of fuel to the atomizer. This means comprises, among other things, a spring 43 which bears upon the top of the worm gear 37, and the other end of which abuts the split ring 44 carried by the 55 outer end of the valve stem 32. This spring yieldingly urges the valve stem in an outward direction, thereby tending to uncover more of the opening 36. In my application above referred to, I have provided manually adjustable means for pushing the valve stem 60

32 inwardly against the tension of the spring 43, and thereby diminishing the rate of flow of fuel to the atomizer.

In my present application, this means comprises an externally and internally 70 threaded sleeve 45 which is supported between two laterally extending bifurcations 46 of the bracket 39. To prevent rotation of the sleeve 45 between these bifurcations, I provide the clip 47 which drops into the slot 75 between the two bifurcations and projects into a notch cut into the flange 45' of the sleeve. A screw 48 of comparatively fine pitch is threaded into the sleeve 45, and carries at its inner end a hardened steel ball 49 80 which engages a concave depression in the outer end of the valve stem 32, this end of the valve stem preferably being hardened.

The screw 48 is provided with an outwardly extending stem 50, upon which is mounted the stop collar 51, which is secured in place by means of the set screw 52. A sleeve 53 rests upon the stop collar 51, and is rotatably mounted upon the stem 50. This sleeve has a lateral projection 54 in 85 which is adjustably mounted the rod or cross bar 55, which is held in its adjusted positions by means of the set screw 56. A segment 57 has its ends rigidly secured to the opposite ends of the cross bar 55, and is provided at spaced intervals with openings 58 adapted to receive the two stop pins 59. These pins are here illustrated as being made in the form of cotter pins and their upper ends project upwardly sufficient to engage 90 the outer end of the arm 60, the inner end of which is provided with a sleeve 61 surrounding the outer end of the stem 50 and secured thereto by means of a set screw 62.

95 From the above description, it will be apparent that when the stem 50 is rotated in one direction, the screw 48 will move inwardly and cause the corresponding movement of the valve stem 32, which will result in a portion of the opening 36 being covered by the valve seat 30, and that when the stem 50 is rotated in the opposite direction, the result will be that a portion of the opening 36 will be uncovered, so that by rotating the stem 50 in opposite directions, the rate of 100 flow of oil to the atomizer can be either increased or diminished. This can be accomplished manually by adjusting the arm 60, but I prefer to provide thermostatically controlled means for automatically effecting 105 such adjustment, and for this purpose I prefer to make use of a heat regulator 63 of well known construction, comprising a suitable motor connected with the arms 64 so as to rotate these arms in opposite directions whenever the motor is placed in 110 action by means of a suitable thermostat 65. Cords or cables 65 may be provided for connecting the arms 64 with the opposite ends 115 of the cross bar 55 as shown in Fig. 2, and 120 125 130

if the regulator 63 is positioned so that the direction of these cables must be changed in passing from the regulator to the cross bar 55, this can be accomplished by means of 5 suitable grooved pulleys 66 rotatably mounted upon a shaft 67 supported by a plug 68 carried by one nipple of the four-way union 22. To permit a certain amount of adjustment of the shaft 67, I prefer to bend one 10 end of the shaft 67 upon itself, as shown in Figure 2, and to secure this end of the shaft to the plug 68 by means of the set screw 69.

From the above description, it will be 15 seen that when the regulator 63 is actuated in the usual way to turn one arm 64 in one direction and the other arm 64 in the opposite direction, the cross bar 55 will turn about the axis of the stem 50 in one direction, thereby moving the screw 48 inwardly and decreasing or entirely interrupting the flow of fuel to the atomizer, but that when the regulator 63 moves the arms 64 in the reverse direction, the stem 50 will be rotated 20 to cause the screw 48 to move outwardly, thereby permitting the spring 43 to expand and thus cause a greater portion of the opening 36 to be uncovered. In this manner the rate of flow of fuel to the atomizer can be 25 increased. The thermostatic control device which I have indicated at 63 and 65 it will be understood is of the type wherein the cable reciprocating arms 64 give the cable a fixed movement in response to the high and low 30 temperature limits of the thermostat 65.

It will, of course, be understood that the motion of the cross arm 55 is transmitted to the stem 50 through the segment 57, the pins 59, and the arm 60. It will also be seen 35 that by properly adjusting the pins 59 in the openings 58, any desired amount of lost motion between the segment 57 and the arm 60 can be obtained, and that the greater the amount of this lost motion, the less will be the movement of the arm 60. Under 40 these conditions, the extent of adjustment of the valve will be small, so that there will be slight variations in the rate of flow of fuel to the burner. It will also be apparent 45 that when the lost motion between the pins and the arm 60 is small, the arm 60 will be moved through a much larger arc, thereby resulting in a greater variation in the flow of oil to the atomizer. Furthermore, by 50 properly positioning the two pins, the limits of the two different rates of flow can be varied as desired within the limits of the apparatus. If the screw 48 is a right hand screw and the two pins are located adjacent 55 the upper end of the segment in Figure 2, the rate of flow of oil to the atomizer will vary between comparatively wide limits, but both of these limits will be smaller than 60 when the two pins are located adjacent the lower end of the segment 57 in Figure 2.

If the movement given the valve through the rotation of the segment 57 is not sufficient to insure the desired rate of flow of oil to the atomizer, the sleeve 45 and the screw can be removed from the valve and 70 replaced by corresponding elements in which the thread of the screw 48 and the corresponding thread of the sleeve 45 have a larger pitch, so that the same angular movement of the arm 60 will cause a greater 75 longitudinal movement of the valve stem.

From the above description, it will be seen that I have provided an oil burner comprising means for controlling the rate of flow of oil to the burner, which is capable 80 of a great variety of variations or adjustments that make possible the easy regulation of the oil burner to maintain any desired temperature under varying conditions of operation, and that these means are comparatively simple in construction and easy 85 to operate. It will also be seen that while my controlling means is entirely automatic in its action, the rate of flow of fuel to the burner can be manually adjusted by moving 90 the arm 60 without in any way disturbing the automatic controlling means.

While I have described the details of construction of the preferred embodiment of my invention, it is to be clearly understood 95 that my invention is not limited to these details of construction, but is capable of other adaptations and modifications within the scope of the appended claims.

Having thus described my invention, what 100 I claim is:

1. A burner comprising an atomizer, means for supplying fuel to said atomizer, including an adjustable valve, and means for controlling the adjustment of said valve, comprising a rotatable element having an arm extending at an angle to its axis, a segment rotatably mounted upon said rotatable element, a pair of stops adjustably mounted on said segment for limiting the movement 105 of said segment relatively to said arm, and a thermostatically controlled element for moving said segment.

2. The combination with a thermostat and a fuel valve controlled thereby of an operating member movable to vary by increments the fuel feed through said valve, an actuating member moving under the control of the thermostat, one of said members forming a sector and the other an arm, and a plurality of stops on the sector for contacting the arm to provide a lost motion connection between the elements, the stops being adjustably positioned on the sector for providing an adjustment of the high and low 120 rates of fuel feed to which the valve is moved by the actuating member.

3. The combination with a thermostat device and a fuel valve of an oil burner controlled thereby, of an operating member 130

movable to vary by increments the fuel feed through said valve, an actuating member moving under the control of the thermostat, one of said members forming a sector and the other an arm, and a plurality of stops on the sector for contacting the arm to provide a lost motion connection between the elements, the stops being adjustably positioned on the sector independently of one another for providing an adjustment of the positions of high and low rates of fuel feed to which the valve is moved by the actuating member.

4. The combination with a thermostatic device and a fuel valve of an oil burner controlled thereby, of an operating member

movable to vary by increments the fuel feed through said valve, an actuating member moving under the control of the thermostat through a fixed movement, one of said members forming a sector and the other an arm, and a plurality of stops on the sector for contacting the arm to provide a lost motion connection between the elements, the stops being adjustably positioned on the sector independently of one another for providing an adjustment of the positions of high and low rates of fuel feed to which the valve is moved by the actuating member.

In witness whereof, I hereunto subscribe my name this 21st day of April, 1923.

FRANKLIN HARDINGE.
